CALCULATING MACHINE, CASH REGISTER,
AND THE LIKE

Ivar Georg André Ljunggren, Karl Matts Vigborg, and Knut Folke Bratt, Stockholm, Sweden, assignors to Kooperativa Förbundet, Förening u. p. a., Stockholm, Sweden

Application March 12, 1938, Serial No. 195,494
In Sweden March 18, 1937

4 Claims. (Cl. 235—6)

The present invention relates to a device for calculating machines, cash registers, and the like, and the device is adapted particularly for shifting coupling wheels or other coupling members. As a matter of fact, it is of a particular importance in, for example, cash registers provided with several totalizers, that the positions of the part shifting the coupling members are carefully fixed, because a reliable operation would otherwise be jeopardized. The heretofore known devices, adapted for the abovementioned purpose and generally called selectors, have, in fact, been of complicated constructions, but in spite thereof they have not, however, operated quite satisfactorily. By the present invention the problem has, however, been solved in a manner, which, as regards construction, is very simple, but yet absolutely reliable, and which provides the apparatus with a positive and reliable operation. Several advantages, obtained by the device according to the invention, will be set forth in connection with descriptions given of two embodiments illustrated on the accompanying drawings and particularly apt for use in cash registers provided with two totalizers.

One embodiment of the invention is illustrated in Figures 1—6.

Figure 1 showing the device in side view,

Figure 2 the same when viewed on the section line II—II, of Figure 1.

Figure 3 shows a section on the line III—III, of Figure 1.

Figure 4 shows some details, assuming positions, which are indicated by dot-dash lines in Figure 1,

Figures 5 and 6 show some further details.

The other embodiment is illustrated in Figures 7—17.

Figures 7 and 8 showing the device in side view, the parts being in different positions.

Figures 9—17 show some details.

Figure 13 showing a section on the line XIII—XIII, of Figure 14.

Both embodiments of the device have the feature in common that with two plates, shaped and provided in a certain manner, there is adapted to cooperate a pin united with the part intended for the shifting. Either, as in the embodiment according to Figures 1—6, the said plates may be

provided on a key bank or, as the embodiment according to Figures 7—17, on a plate member, or the like, rigidly united with the frame of the machine. In order that the first-mentioned way of mounting shall be clearly visible on the drawings it is necessary to draw the parts included

in the device on such a large scale that all parts of the machine cannot be shown in Figures 1—6. Yet, when describing the embodiment according to Figures 1—6, a clear idea of the mode of operation of the device will be obtained by reference being hereinafter had also to the parts of the machine shown in Figures 7 and 8.

In the embodiment according to Figures 1—6, the two abovementioned plates, which in the said figures are indicated by A, and B, are movable towards and away from each other by means of pins 2, which engage guide slots 1 and which are displaceably united with quite an ordinary key bank 4 provided with a ratch 3 for retaining keys when depressed. The guide slots 1 are given a length corresponding as exactly as possible to the maximum displacement of the plates A, B, and by the action of tension springs 5 the said plates tend to assume their neutral positions shown in full lines on the drawings. As is best seen from Figure 5, in which the plate A is shown separately, each of the plates A, B, is provided, on one hand, with two cam or guide surfaces 6, 7, formed from one end portion of the respective plate and forming an angle to each other, and, on the other hand, with two cam surfaces 8. Of the eight keys provided in the key bank 4 the keys of the set indicated by 10A are intended to be actuated by one salesman and the keys of the set indicated by 10B intended to be actuated by another salesman. Two keys of each group are provided with pins 11, adapted to cooperate with the guide surfaces 8. The two remaining keys of each set have no such pins and when the said keys are depressed the plates A, B, are not actuated in any way. Yet, by depressing the said keys certain data may be entered into the apparatus and by means of special members, which, however, have no particularly intimate connection with the present invention, markings, corresponding to the said data, may be obtained, for example, in the printing mechanism of the apparatus.

12 indicates a member, which is put into a reciprocating motion, when the cam members 47, shown in Figures 7, 8, and 16, are turned. In the embodiment according to Figures 1—6 the member 12 is provided with an oblong slot 14. In the said slot slides a pin 13, which is rigidly united with a link member 49, the other end of which has jointed connection with one end of an arm 48, which is adapted to rock on a stationary shaft 31, one end of the bar 50, shown in Figures 7, 8, and 17, having in its turn jointed connection with the other end of the said arm 55.

48. The other end of the said bar is united with one of two arms 18, which are adapted to rock on a stationary shaft 60 and which between themselves support a shaft 61, on which coupling wheels 51 are rotatably mounted. The 5 coupling wheels 51, which mesh with transmission wheels 55, mounted on the shaft 60, may, when the arms 18 are rocked, be brought into mesh either with the totalizer wheels 52C, rotatably mounted on the shaft 62, or with the 10 totalizer wheels 52D, rotatably mounted on the shaft 63. In such a case the totalizer actuating racks 54 of the apparatus, which racks are supported by amount setting members 26 and with 15 which the wheels 55 are in mesh, and the totalizer wheels of one totalizer or the other. The condition for obtaining such coupling together, as above referred to, is however, that the rocking movement, which the arms 18 have to perform for this purpose, is exactly as great as required. 20 From the description of the mode of operation of the device, given in the following, it will be seen that this really is the case.

If one of the keys in Figure 1, which have no 25 pins 11, is depressed, the pin 13, which, in its initial position, is located in the part—corresponding to the diameter of the pin—of the opening 21 in a plate member 20, secured to the key bank 4, which plate member is shown separately 30 in Figure 6, during the displacement of the member 12, which displacement is directed towards the plates A, B, will enter between the cam surfaces 6 of the said plates, which surfaces jointly 35 form a rectilinear slot for the pin. The initial position and the terminal position of the pin lying at an equal distance—each on its side—from a central line, drawn through the link member 49 and the joint 64 of the arm 48 perpendicularly to the direction of motion, the arm 48, in the 40 terminal positions, will be equally positioned and the arms 18 thus remain in their positions shown in Figure 7, and no coupling together of setting members and totalizer wheels takes place. If, 45 however, one of the keys, having a pin 11, is depressed, either of the plates A, B, is displaced, on account of the cooperation of the said pin with one of the cam surfaces 6, to operative position and, on the drawings, the plate B is indicated by dot-dash lines, in Figure 1, and shown in full 50 lines, in Figure 4, when assuming operative position. The depressed key being retained in its depressed position by the ratch 3, the respective plate will, of course, also remain in its operative position in spite of the action of the spring 5. In such a case a pin 19, which is secured to 55 the plate A and located at some distance from the cam surface 6 of the plate in question, cooperates with the cam surface 6 of the plate B. Thus, the pin 19 will provide for a fixing of the 60 positions of the plates in relation to one another, in case the grooves 1 should not be exactly adjusted. The length of the displacement of the plates preferably is so adjusted that the point, 65 formed by the cam surfaces 6, 7, will be located far enough beside the centre of the pin 13 when one of the plates assumes operative position; this in order to assist a good cooperation between the pin 13 and the cam surfaces 7.

When the plate B assumes its operative position, indicated by dot-dash lines in Figure 1, and the pin 13 is moved towards the said plate the 70 guide surface 7 of the latter will cooperate with the pin 13, which thus is caused, as shown in full lines in Figure 4, to deviate from its rectilinear movement. It should be observed that, when

such cooperation has been obtained, it is impossible to depress any further key. When the pin 13 cooperates with the guide surface 7 a rocking motion, because of the length of the groove 14 and the length and inclination of the guide surface 7, will be imparted to the arms 18, via the bar 50, the arm 48, and the link member 49, and during the rocking motion performed by the arms 18 in such a case a coupling together of the setting members and totalizer wheels of the apparatus is effected by moving the coupling wheels 51. In order to further guarantee the positive operation of the device the opening 21 of the plate member 20 secured to the key bank 4, into which opening the pin 13 extends, is so shaped 15 that the edge thereof, together with one of the guide surfaces 7 of the plates A, B, adjusted in operative position, forms a groove for the pin 13. Thus, the latter is prevented from performing any such movement as could result in an indefinite fixing of the turning motion of the shaft 16 and therewith unreliable operation.

In the embodiment illustrated in Figures 1-6 the plates A, B, are, as above described, movable towards each other. In the embodiment according to Figures 7-17 the said plates, which are movable away from and towards each other, are replaced by swingable plates, which on the drawings are indicated by C, D. By means of a pin 22, serving as a pivot, the last-mentioned plates 30 are provided on a plate member 23 provided in the machine (see Figures 7, 8, 13, and 14). In a manner corresponding to that in the embodiment according to Figures 1-6, tension springs 5 tend to retain the plates C, D, in their neutral 35 positions shown in Figures 7 and 13. In order to obtain greater clearness, Figures 7 and 8 show only one of the keys of the group 10B, in Figure 1. In the said embodiment of the device the plates C, D are not intended to be shifted by 40 means of the keys, (the transaction or account keys), due to which the latter and the key bank, respectively, need not be constructed in a special manner differing from that of the amount key banks. In order to obtain a shifting of the 45 plates C, D, the rocking movements of which are limited by projections 24 on the plates being adapted to cooperate with shoulders or pins 25 on the plate member 23, the following provision is made:

On a transaction setting member 26 there is rockably mounted a member 27, which is best visible in Figures 11, 12, and which member is provided with an angular portion 28. By means of a tension spring 29, and a pin 30, the member 27, during the up-and-down motion of the member 26, is held in its position shown in Figure 7 relatively to the setting member. Further, there is a plate 32 (best shown in Figures 9 and 10), which is rockably mounted on the stationary 60 shaft 31 and which is provided with a slot 33. The plate 32, which, in addition to the slot 33, is provided with bent portions 34C, 34D, tends, by the action of a tension spring 35, to assume the 65 position shown in Figures 7 and 11, in which case the portion 34C rests against a stationary guide member 36, which serves as a lateral guide for the plate.

In Figure 7 all parts assume their neutral or normal positions. Now, however, for example, the 70 key, shown on the drawings and indicated at 10B, is depressed and the machine is started. Cam discs 39, secured on the main shaft 38 of the machine then begin to rotate, the arms 46 being swung upwards and finally assume their upper 75

terminal position shown in Figure 8. The transaction setting member 26, which, in a manner corresponding to that of the amount setting members, by the action of a spring 44 on the arms 45 also is moved upwards, will, however, stop when the rack tooth 37, which corresponds to the depressed key, strikes against the free end of the said key. Thus, in the present case the transaction setting member stops in the position shown 10 in Figure 8.

A transverse shaft 42, which is united with the arms 46 by means of link members 40 and which is guided in slots 41 in the setting rack, has received an upwards directed movement when the said 15 arms were swung upwards. In such a case the shaft 42 has entered the recess 33 provided in the plate 32 and, because of the shape of the said slot, it has imparted to the plate 32 a swinging movement directed towards the plates C, D. The 20 portion 34D of the plate 32, when the same has hit the portion 28 of the member 27 and the latter has, in turn, hit a bent portion 43 shaped from the plate D, has swung the plate D against the 25 action of the spring 5 to its position shown in Figures 8 and 15.

Thus, the plate D assumes this position when the member 12, during the rotation of the cam discs 41 secured on the shaft 38, pulls the pin 13, uniting the member 12 and the link member 49, 30 towards the plates C, D. In such a case the pin 13, by the groove, formed by the cam surface 7 of the plate D, and the slot 21, is caused to assume the position shown in Figure 8, and by the pin deviating from its rectilinear path of movement 35 the arm 48, which is mounted on the shaft 31 and which, in fact, by means of the link member or the bar 49, is united with the pin 13, is given a rocking motion. This motion is transmitted by the bar 50 to the arms 18 supporting the coupling 40 wheels 51. The coupling wheels, therefore, enter into mesh with the totalizer wheels indicated by 52D. Thus, the said totalizer wheels, from the totalizer actuating racks 54 of the amount setting racks 56, via the transmission wheels 55, will take 45 the amount entered on the amount keys by the salesman in question, when the arms 45 united with the setting racks 56, during the downwards directed swinging motion of the arms 46, are taken along by the transverse member 53 provided between the arms 46. Yet, during this operation the pin 13 is retained in its position shown in Figure 8, in spite of the fact that the member 27 accompanies the transaction setting member 26 to the initial position. Not until after all 50 members 56 and 26, respectively, have reached the last mentioned position does the member 12 displace the pin 13 to its initial position and by this the machine has accomplished one working stroke.

In order that the one of the plates C, D, which has been the last one to assume operative position, shall be positively returned to inoperative position when the opposite plate is rocked from inoperative to operative position each plate C, D 65 is provided with a projection 57, which, in the shown embodiment, serves also as a member of attachment for the spring 5. The said projection is so provided that, when a plate is rocked from inoperative to operative position, the opposite plate is taken along and shifted from operative to inoperative position by the projection 57 in question striking against the edge of the opposite plate.

If such a transaction or account key has been 70 depressed that the member 27 stops in such posi-

tion that its portion 28 is given no possibility of cooperating with one of the two shoulders 34C, or 34D, of the plate 32, the plates C, D remain in their positions shown in Figure 7. In such a case the pin 13 will pass between the cam or guide 5 surfaces 6 of the last mentioned plates, the said surfaces being turned against each other. In such a case no shifting of the coupling wheels 51 is effected but the machine completes its working stroke without the coupling wheels moving 10 from their inoperative position shown in Figure 7. Consequently, in such a case neither do the totalizer wheels 52D nor the wheels 52C take any value.

As is clear from the foregoing the machine, by 15 the device hereinbefore described and shown in Figures 7-17 is given a very positive operation. Moreover, the parts included in the device are of very simple constructions. Further, no special driving members are required for obtaining a 20 shifting of the plates C, D, members already included in the machine being used for such purpose. That the key banks may be embodied in the usual manner has already been pointed out. Finally, the device makes it impossible to obtain 25 a simultaneous shifting of the plates C, D, and thereby breaking of the pin 13 is prevented.

The amount setting members operating quite independently of the transaction setting members 30 the operations of the first-mentioned members and of the tens transmitting device, which is intended to be used in the present case, are not particularly described in the present specification, the said tens transmitting device being made the object of a separate application (Swedish 35 patent application No. 1958/1937).

Several embodiments may, of course, be devised within the scope of the invention. Thus, the shape of the plates C, D, may vary and, if it should prove suitable, each of them may be provided on its special pivot.

Having now described our invention, what we claim as new and desire to secure by Letters Patent is:

1. In a calculating machine or similar apparatus having a rotatable main shaft, a first group of keys, a second group of keys and a coupling wheel or similar member to be shifted from a neutral position to either one of two operative positions, the combination with a lever pivoted on a fixed fulcrum to control said shiftable member, of a guide pin, a link pivotally connecting said guide pin to said lever, means to reciprocate said guide pin upon each rotation of said main shaft, a first cam and a second cam movable towards and away from one another, said cams having guide surfaces facing one another and oppositely inclined cam surfaces, means to normally hold said cams in a spaced relationship in which said guide surfaces form between them a guide path for said pin to allow reciprocation thereof substantially without displacement of the lever, whereby said shiftable member is retained in its neutral position when no key in either of said two groups has been depressed, means to displace said first cam towards said second cam upon depression of a key of said first group so as to close said path and to cause a cooperation between the reciprocating pin and the cam surface of said first cam whereby the movement of the pin is deviated in one direction and said shiftable member, through said link and lever, is shifted to its first operative position, and means to displace said second cam towards said first cam upon depression of a key of said second group to 75

cause a cooperation between the reciprocating pin and the cam surface of said second cam, whereby the movement of said pin is deviated in the opposite direction and the shiftable member is shifted to its second operative position.

5. 2. A machine, as claimed in claim 1, comprising a stationary guide plate provided with an aperture through which said pin extends, said aperture having two guide surfaces adapted to 10 cooperate with the cam surfaces of said cams in such a manner that one guide surface forms an inclined guide slot for said pin with the cam surface of said first cam when the same has been displaced towards the second cam, and the other 15 guide surface forms an oppositely inclined guide slot for said pin with the cam surface of the

second cam when the latter has been displaced towards the first cam.

3. A machine, as claimed in claim 1, in which said cams are formed as plates, one of said plates having a projection limiting their mutual displacement towards one another.

4. A machine, as claimed in claim 1, in which the two cams are formed as rotatable plates having projecting portions, and means comprising stationary abutments arranged for cooperation 10 with said projecting portions to limit the rocking movements of said plates.
